[57] CLAIM

The ornamental design for a combined petroleum fuel spillage and overfill containment tank, as shown and described.

DESCRIPTION

FIG. 1 is a top perspective view of a combined petroleum fill spillage and overfill containment tank showing our new design;

FIG. 2 is a front elevational view thereof;

FIG. 3 is a left side elevational view thereof, the right side being a mirror image;

FIG. 4 is a rear elevational view thereof;

FIG. 5 is a top plan view thereof; and

FIG. 6 is a bottom plan view thereof.

Fig. 1.

Fig. 2.

*Fig. 3.**Fig. 4.*Fig. 5.

Fig. 6.
